UNITED STATES PATENT OFFICE.

OMA CARR, OF BUENAVISTA, VIRGINIA.

FACE-PLATE FOR GRINDING-MILLS.

SPECIFICATION forming part of Letters Patent No. 772,642, dated October 18, 1904.

Application filed December 17, 1903. Serial No. 185,531. (No model.)

To all whom it may concern:

Be it known that I, OMA CARR, a citizen of the United States, residing at Buenavista, county of Rockbridge, State of Virginia, have 5 invented certain new and useful Improvements in Face-Plates for Grinding-Mills, of which the following is a specification, reference being had therein to the accompanying drawings, in which—

10 Figure 1 is a part sectional side elevation of the assembled machine; Fig. 2, a vertical sectional view of a portion of the grinding-disks; Fig. 3, a face view of one grinding-disk; Fig. 4, a similar view of the other grinding-disk; Fig. 5, a detail vertical sectional view of a portion of one of the grinding-disks, showing a slightly - different form of face-plate.

15 The ordinary attrition or face-plate grinding-mills of both horizontal and vertical types employ plates or disks upon which are cast various forms of breakers or nubs, the breakers on one disk being so arranged with respect to those on the other that the material placed 20 between the disks is ground and broken up, the extent of grinding being dependent upon the clearance - space between the grinding-breakers. The breakers or nubs are formed integral with the face-plates, such plates being 25 removable in order that new plates may be inserted when the breakers have become worn to such an extent as to impair the efficiency of the mill. The speed of these grinding-disks is very high and the wear upon the 30 surfaces is rapid, so that to maintain the efficiency of the apparatus frequent renewals of the face-plates are necessary.

35 It is one of the objects of this invention to provide a face-plate made up in segments, 40 each segment being independently removable, and to provide each of these segments with independent removable breakers or grinding devices which are so mounted as to present numerous cutting-surfaces to the material 45 worked upon, said surfaces or cutting-points changing their position during the rotation of the grinding-disks.

50 A further object of the invention is to provide the face-plates with removable breakers or nubs having numerous sharp cutting edges.

Referring to the various parts by numerals, 1 designates a pair of grinding-disks, each of which is rigidly mounted upon the inner end of a shaft 2. The material to be worked upon is fed through the center of one of these disks 55 by means of a hopper or chute 3. Each disk is provided with a series of segmental face-plates 4, which fit closely within the annular outward-extending marginal flange 5 of the disk. Each face-plate is provided with a plurality of annular series or rows of apertures 6, in which snugly fit horizontal outward-extending screws 7. These screws are provided at their inner ends with enlarged heads 8, which bear against the inner face of the disk and lie 60 between the same and the face-plate. These face-plates are secured rigidly to the disks by means of bolts 9, whose heads are counter sunk in the face-plate. By this means the bolts 9 serve to not only hold the face-plates 70 in position on the disk, but also to maintain the breakers 7 in position in the face-plates. The breakers or grinding devices 7 of one disk are complementary to the grinding devices in the opposite disk, the breakers of 75 one disk forming races or ways in which the breakers or grinding devices of the opposite disk travel. The projecting part of each breaker or grinding device is formed with a screw-thread or a similar annular or spiral 80 groove in order that it will present numerous sharp cutting edges to the material. While the bolts 9 will secure the segments of the face-plates to the disks, the cutting devices or breakers 7 will be free to rotate independently 85 in the face-plates, so that fresh cutting-points will be presented to the material during the operation of the apparatus. In order to secure this free rotation of the cutting devices, the face-plate segments are provided 90 with lugs 4^a to bear against the disk, and thereby prevent the bolts 9 from clamping the heads 8 against the disk tightly enough to prevent the rotation of the screws 7, as shown in Fig. 5.

95 It will of course be understood that the grinding devices or breakers may project any desired distance beyond the face-plate and that the clearance-spaces between the breakers or grinding devices of the two disks 100

may be as large as desired to adapt the apparatus to the work for which it is designed.

It will be readily understood from the foregoing description that when the grinding-disks are rapidly rotated in opposite directions the rows of screws or other many-pointed grinding devices will present numerous cutting contacts or points to such material as may be run between them, and because of the fact that the cutting devices rotate in the face-plates said devices will last a great while and maintain the efficiency of the apparatus. It is also obvious that it will be only necessary to remove the grinding devices when they become worn or broken, the face-plates lasting indefinitely. It will of course be understood that this apparatus may be employed in a horizontal position as well as in a vertical position.

Having thus described my invention, what I claim as new, and desire to secure by Letters Patent, is—

1. A grinding device consisting of a disk, a removable face-plate, and removable rotatable breakers or grinding devices removably secured to the face of the disk by the face-plate.

2. A grinding device consisting of a disk, a plurality of annular rows of breakers or grinding devices secured thereto, said devices being formed with a plurality of cutting-points and being freely rotatable independently of each other and the disk.

3. A grinding device consisting of a disk, a face-plate removably secured thereto, and a plurality of rows of grinding devices or breakers rotatably mounted in said face-plate.

4. A grinding device consisting of a disk, a face-plate removably secured to the carrier-plate, and a plurality of rows of breakers or grinding devices formed with a plurality of cutting-points and rotatably mounted in the face-plate.

5. A grinding device consisting of a disk, a face-plate formed in segments, a plurality of rows of breakers or grinding devices rotatably mounted in the face-plate and formed with heads on their inner ends, said heads lying between the disk and the face-plate, and means for removably securing the face-plate segments to the disk, whereby the grinding devices are secured in position.

6. A grinding device consisting of a disk, a face-plate formed in segments, a plurality of rows of breakers or grinding devices rotatably mounted in the face-plate and formed with

heads on their inner ends and with a plurality of annular cutting-points at their outer ends, said heads lying between the carrier-plate and the face-plate, and means for removably securing the face-plate segments to the carrier-plate, whereby the grinding devices are secured in position.

7. A grinding device consisting of a disk, a face-plate secured thereto, and a series of freely and independently rotatable grinding devices carried by said face-plate.

8. A grinding device consisting of a disk, a plurality of annular rows of breakers or grinding devices secured thereto and provided with a series of annular cutting-points, said devices being held rotatably in the disk.

9. A grinding device consisting of a disk, a face-plate formed in sections and removably attached to the disk, a plurality of breakers mounted in the face-plate and formed with heads on their inner ends and annular cutting edges on their projecting ends, said heads lying between the disk and the face-plate, and means for removably securing the face-plate sections to the disk, whereby the breakers are removably secured in position.

10. A grinding device consisting of a disk, a face-plate and means for removably securing it to the disk, a series of grinding devices rotatably mounted in the face-plate and formed with heads on their inner ends, said heads lying between the disk and the face-plate.

11. In combination with a grinding-disk, a face-plate secured thereto and made up of independently-removable sections, and breakers attached to the face of the disk by said face-plate, these breakers being independently removable from the face-plate sections, and each being provided with a series of annular cutting edges.

12. In a grinding-machine, the combination of a pair of rotatable grinding-disks arranged face to face, a plurality of rows of grinding devices on the face of each disk, the rows carried by one disk working between the rows carried by the other disk and the working faces of each grinding device being screw-threaded to provide a series of annular cutting edges.

In testimony whereof I hereunto affix my signature, in the presence of two witnesses, this 16th day of December, 1903.

OMA CARR.
